INVENTOR

William X. Stevens.

UNITED STATES PATENT OFFICE.

WILLIAM X. STEVENS, OF WASHINGTON, DISTRICT OF COLUMBIA.

MECHANICAL TOY

SPECIFICATION forming part of Letters Patent No. 274,148, dated March 20, 1883.

Application filed February 8, 1883. (No model.)

To all whom it may concern:

Be it known that I, WILLIAM X. STEVENS, a citizen of the United States, residing in the city of Washington, District of Columbia, have 5 invented a Mechanical Toy, of which the following is a specification.

The object of my invention is to produce a mechanical toy to imitate the game of leap-frog, to make the same attractive and entertaining to children, yet simple of construction and inexpensive. To this end it is in the nature of a pair of wheels to be rolled upon the floor, supporting and operating two or more figures to pass over each other alternately; and 10 it consists in the construction and combination of parts hereinafter described and claimed, reference being had to the accompanying drawings, in which—

Figure 1 is a perspective view of my invention, showing two frogs as actors; and Fig. 2 is a side elevation, showing three boys as the actors.

A represents the actors, which may be frogs or boys, or any other figures of animate or inanimate things. These actors are hung to swing freely upon cross-bars B by means of wire loops C. The cross-bars are secured at their ends to spokes D of the wheels E. The wheels are provided with eyes at their centers 25 to serve as bearings in which the two ends of a bail, F, are supported. This bail may be long enough to serve as a handle for the child to draw the toy by, or its central part may be extended just enough away from the wheels to 30 allow the actors to pass it freely. When the wheels are rolled along the floor the actors will revolve over each other, all the time hanging beneath the bars in an upright position. The distance of a cross-bar B from the rims 35 of the wheels is the distance required for the body of the actor between the bar and the floor. The loops C are made long, in order that the actor's center of gravity may be far below the support, to make him hang right side 40 up, and the purpose of the elongated openings in the loops is to permit the actor to land on the floor before his supporting cross-bar reaches its lowest point, thus permitting the actor to 45 rest on the floor until his cross-bar rises to 50 the top of the loop, then to be taken up quickly, thereby to imitate the game of leap-frog better than if the actors continually hung on the bars without stopping on the floor.

Any substitute for the wire loops C—such 55 as flexible or elastic supports—may be used,

or the actors may be hung too high to hit the floor. Any number of actors may be hung upon one bar, and any number of bars may be used. The wheels may be of any style which will carry and show the actors well. On the 60 same principle, the wheels may have the bars extending, like cranks, from their outer faces to carry the actors; or an axle having bends in it to form two cranks to carry the actors over in circles side by side might be used as a substitute for the cross-bars. By using relatively 65 smaller actors the wheels may have a full-length axle carrying a figure, over which the actors would pass, as dogs leaping over their trainer, for example. By making a single 70 wheel or roller thick enough to stand on its edge, and providing the same with bars projecting from its sides and actors hung on the bars, a modification of this toy would be produced. An actor may also be hung to a wheel 75 by flexible cords, without the use of cross-bars, the length of the cords being greater than the circumference to allow the figures to land ahead of the center of the wheel, and to be lifted after the center of the wheel has passed the same, as with the bars and loops.

What I claim as my invention, and wish to secure by Letters Patent, is—

1. The combination, with a hoop or wheel, of 80 a toy figure hung to the same, between the axis and circumference thereof, as described.
2. The combination, with a hoop or wheel, of 85 a toy figure hung to the same by a connection longer than the distance from its point of attachment to the rim of the wheel.
3. Two wheels connected together at a little 90 distance within their rims by two or more cross-bars, in combination with figures of frogs or other objects loosely hung upon said bars, 95 to remain below the same while revolving with the wheels, as shown and described.
4. One or more wheels having bars projecting from the side or sides thereof, and figures 100 of any objects loosely hung to said bars, to remain below the same while revolving with the wheel, as shown and described.
5. The combination, with a wheel or wheels, 105 of toy figures loosely hung thereto at a distance from their axis of revolution, substantially as shown and described.

WILLIAM X. STEVENS.
